UNITED STATES PATENT OFFICE.

NELSON E. AUSTIN, OF DANBURY, CONNECTICUT.

DRAINAGE AND IRRIGATION TILE.

No. 901,582.

Specification of Letters Patent.

Patented Oct. 20, 1908.

Application filed January 18, 1908. Serial No. 411,527.

To all whom it may concern:

Be it known that I, NELSON E. AUSTIN, a citizen of the United States, residing at Danbury, in the county of Fairfield and State of Connecticut, have invented certain new and useful Improvements in Drainage and Irrigation Tiles; and I do hereby declare the following to be a full, clear, and exact description of the invention, such as will enable others skilled in the art to which it appertains to make and use the same.

My invention relates to certain improvements in drainage and irrigation tiles, and consists in the construction and arrangement 15 of parts such as will be hereinafter fully described and then particularly pointed out in the claims which conclude this description.

In the accompanying drawing which forms a part of this application Figure 1 is a perspective view of the preferred construction 20 of my improved tile—Fig. 2 a perspective view of a modified form of construction, and Fig. 3 a cross sectional elevation showing my preferred construction of tile in its underground position.

Similar numbers of reference denote like parts in the several figures of the drawing.

Referring to Figs. 1 and 3, my improved tile is preferably an integrally molded structure; at the bottom of which is a water conduit 1 which extends lengthwise of the tile, while at the middle portion of the tile is a horizontally disposed web 2 which is perforated as seen at 3, said web serving as a 35 roof to the conduit. The sides 4 of the tile extend upwardly beyond the web 2 so as to form a trough the floor of which is the web itself.

In utilizing my improvement tiles constructed as above are placed in a suitable excavation underground, the abutting ends of the tiles being preferably cemented together so as to prevent undue leakage of water. Gravel, cinders or other analogous material 45 is then placed within the trough-like receptacle at the upper part of the tiles to about the horizontal level of the sides 4, and the whole is then covered up to a suitable depth with the ordinary earth.

At Fig. 3, 5 represents the gravel or similar material resting upon the perforated web 2, and held in place by means of the sides 4, and 6 represents the ordinary earth or soil which surrounds the tile and the gravel.

When my improved tile is used for the purposes of irrigation water is introduced

in any suitable and ordinary manner within the conduit 1, and the ends of the tile system are closed by suitable gates or other ordinary means so that said water may rise 60 through the perforations 3 and gravel 5 into the soil above and thence be drawn up toward the surface and into the surrounding portions of the soil by capillary attraction, the gravel or other similar substance 5 preventing the soil from washing into the tiles or clogging the perforations 3.

The provision of the trough-like receptacle at the upper portions of the tile is an important feature of my improvement, since 70 the gravel or similar material is thereby held in position and prevented from scattering into the surrounding soil, and the sides 4 which form this trough serve as anchorages to preserve the proper position of the tile 75 in its underground state.

At Fig. 2 I have shown the tile formed with opposite horizontally disposed ledges 7 immediately above the conduit, upon which ledges rests a perforated cover plate 8, the 80 sides of the conduit being extended above the cover plate, so that the latter together with said sides form the trough-like receptacle, this cover plate performing the same function as the perforated web 2. There is, 85 therefore, no substantial difference between the constructions shown at Fig. 2 and Fig. 3, and my invention is not limited in this respect.

When concrete is near at hand, continuous 90 lengths of tiling may be molded directly within the excavation itself, and in this instance the construction shown at Fig. 2 would be utilized, and the perforated cover plates 8 would be made of wood or other 95 suitable material.

In utilizing my improvement for drainage purposes the ends of the tile system would be open and would be in communication with any suitable means for carrying off the 100 water.

Having thus described my invention what I claim as new and desire to secure by Letters Patent is:

1. A drainage and irrigation tile containing at its lower portion a conduit extending lengthwise of the tile, and having at its middle portion a horizontally disposed perforated roof directly over said conduit, the sides of the tile being extended upwardly in 105 a vertical plane to form in connection with said roof a trough-like receptacle, while the

conduit itself has no outlet except through said perforated roof.

2. A drainage and irrigation tile having vertically disposed sides and provided at the 5 top with an open trough and at the bottom with a conduit, said trough and conduit extending lengthwise of the tile, and a perforated horizontally disposed web separating said trough and conduit and acting as 10 the roof of the latter and the floor of the former and affording the only outlet for said conduit.

3. A drainage and irrigation tile comprising a water conduit pipe extending lengthwise of the tile, and an open trough parallel 15 with said pipe and having its outer sides co-

incident with the outer sides of said conduit, said trough and conduit being separated by a perforated partition.

4. A drainage and irrigation tile comprising 20 a water conduit pipe and a vertically disposed trough formed integral and in juxtaposition, the wall of the pipe being closed except as to openings in said wall adjacent to the trough whereby communication is established between said pipe and trough.

In testimony whereof I affix my signature in presence of two witnesses.

NELSON E. AUSTIN.
